UNITED STATES PATENT OFFICE.

JONAS NORTHROP, OF HOPEDALE, MASSACHUSETTS, ASSIGNOR TO HOPEDALE MANUFACTURING COMPANY, OF HOPEDALE, MASSACHUSETTS, A CORPORATION OF MASSACHUSETTS.

WARP STOP-MOTION FOR LOOMS.

1,178,819.

Specification of Letters Patent. Patented Apr. 11, 1916.

Application filed April 17, 1914. Serial No. 832,482.

To all whom it may concern:

Be it known that I, JONAS NORTHROP, a citizen of the United States, residing at Hopedale, in the county of Worcester and State of Massachusetts, have invented certain new and useful Improvements in Warp Stop-Motions for Looms; and I do hereby declare the following to be a full, clear, and exact description of the invention, such as will enable others skilled in the art to which it appertains to make and use the same.

The present invention relates to an improvement in warp stop motions for looms.

The object of the invention is to reorganize and improve the construction of warp stop motions in order to produce a construction of high efficiency and economical operation.

To these ends the present invention consists of the warp stop motion hereinafter described and particularly defined in the claims.

In the accompanying drawings illustrating the preferred form of the invention, Figure 1 is an end elevation of a loom provided with the present warp stop motion; Fig. 2 is a plan of one end of the feeler rock shaft and associated parts; and Fig. 3 is a plan of a portion of the stop motion illustrating the relative position in plan of the bunter on the lay and the dagger on the stop motion.

The illustrated embodiment of the invention is described as follows:—The warp W runs from the warp beam over the whip roll R, thence through the warp detectors to the heddles H, and thence to the breast beam B. The lay L supported on the swords S actuated by the crank shaft C are all arranged as usual in looms. The shipper lever M is of the ordinary construction. These parts are supported by the frame F in the usual manner. The detectors or drop wires 1 are supported on rods in the usual manner, and when a warp thread breaks, the wire supported by the broken thread falls and arrests the weft detector or feeler 2 which is supported on the rock shaft 3. The rock shaft has secured to it the lever 4 which is provided with a hole to receive a pin 5 by which the rock shaft actuating lever 6 is pinned to the arm 4. A thumb screw 7 is used to hold the pin in place. When it is desired to disconnect the feeler from its actuating lever 6, the thumb screw 7 is

loosened, the pin 5 is withdrawn from the hole in the end of the lever 6, and the oscillations of the actuating lever 6 are no longer transmitted to the rock shaft 3. The rock shaft lever 4 is provided at its extreme end 60 with a counter-balance weight 9. The rear end 10 of the actuating lever 6 is provided with a hole which receives a pin 11 from the casting 12 which is supported on the feeler actuating rod 13. Provision for adjustment of the position of the casting 12 on the feeler actuating rod 13 is secured by means of nuts 14 which screw on the rod 13 and hold the casing 12 in adjusted position. A cotter pin 8 holds the pin 11 in 70 the hole in the end of the actuating lever 6. The lower end of the feeler actuating rod 13 is pivotally connected to the cam operated lever 15 which is pivoted on the pin 16 supported in the frame F of the loom, a 76 cotter pin 17 holding the lever in place. A coil spring 20 on the pin 16 normally tends to turn the cam operated lever 15 in the direction to lift the rear end which is attached to the feeler actuating rod 13. This 80 tends to hold the lever against the cam 21 mounted on the shaft 22 by which the lever 15 is actuated. This cam engages a cam block 23 which is yieldingly supported by the spring 24 and is slidably mounted on the lever 15. The cam block 23 has a stem 25 which is encircled by the spring 24 and projects downward through the boss 26 on the side of the lever 15. The cam block itself is embraced by the lips 30, as shown in plan 85 in Fig. 3.

The above described arrangement is such that with each rotation of the shaft 22 the lever 15 is oscillated to cause oscillating movements to be imparted to the feeler 2, 95 the cam lever 15 pulling downward upon the feeler actuating rod 13 and swinging the feeler to the right, and the spring 20 lifting the rod and moving the feeler to the left. When the feeler is arrested in its forward movement (to the right, as seen in Fig. 1) the cam block 23 gives away under the pressure of the cam and permits the cam to complete its movement without further movement being imparted to the lever 15. This 100 therefore holds the lever 15 in its upper position. When the feeler is arrested in its rearward movement (toward the left, as seen in Fig. 1) under the influence of the spring 20, the lever 15 comes to rest and 105 110

the cam 21 leaves the cam block 23. In either of these events, the right-hand end of the lever 15 occupies the position above its normal position and such as to hold the 5 dagger 31 in the path of motion of the bunter 32 mounted on the sword S of the lay. The dagger 31 is mounted on the rod 33 being secured thereto by a set screw 34. On its outer end it is provided with a 10 pin 35 which passes through the slot 36 in the front end of the lever 15. The rod 33 is pivotally connected at 36 to the lower end of the knock-off lever 40 pivoted at 41 on the frame of the loom and provided with a 15 shipper lever engaging head 42 which normally engages the shipper lever M resting lightly against it. When, however, the dagger is held in the path of motion of the bunter 32, the bunter 20 strikes the dagger and causes a pull to be exerted upon the rod 33 thereby turning the knock-off lever 40 and causing its upper end 42 to knock off the shipper lever M, and so stop the loom.

25 A peculiar feature of this stop motion resides in the use of the give-away device or spring supported cam block 23 which yields when the feeler is arrested by engagement with a drop wire so that the feeler operating lever 15 holds the dagger 31 in position 30 to be struck by the bunter on the lay.

Another feature of the construction resides in that by virtue of which the feeler operating lever 15 is operated in one direction by a cam and in the opposite direction by a spring. This secures simplicity of construction and certainty of operation.

The details of construction of the drop wire support do not form any part of the 40 invention, as that may be of any suitable form. In the illustrated embodiment the drop wires are supported upon the drop wire bars 50, in turn carried by the heads 51 which are supported by the rods or brackets 45 52, in turn carried by the adjustable bracket supports 53, adjustably secured to the frame of the loom. It will be observed that in the illustrated embodiment of the invention both edges of the feeder bar are used to 50 engage the drop wires—the front edge of the feeler bar engages a front drop wire, and the rear edge of the feeler bar engages a rear drop wire, with the result that the feeler bar is arrested in a position which is 55 substantially the same, whether it happens to be moving in one direction or the other at the time, so that the feeler operating lever 15 always occupies substantially the same position, whether it is arrested in its 60 forward or rearward movement, thereby bringing the dagger 31 opposite the bunter 32 when arrested in either direction of movement.

The present invention is not limited to 65 the illustrated embodiment, as it may be em-

bodied in other forms within the scope of the following claims:—

1. A warp stop motion for looms having, in combination, warp detectors, a feeler, feeler operating means including a feeler 70 operating lever and a rotating cam, the feeler operating lever being provided with a give-away device mounted thereon constructed to yield when the feeler is arrested in motion in one direction. 75

2. A warp stop motion for looms having, in combination, warp detectors, a feeler, a lever connected with the feeler for actuating it having a give-away device on it, a cam adapted to engage the give-away device, a spring acting on the lever to move it in a direction opposite to that in which it is moved by the cam, knock-off means, a dagger connected with the knock-off means, a bunter connected with the lay, and connections between the feeler actuating lever and the dagger having provision for moving the dagger into the path of motion of the bunter when the feeler is arrested by engagement with the warp detector. 85

3. A warp stop motion for looms having, in combination, warp detectors, a feeler, and feeler actuating means including a give-away device and a rotating cam for engaging the give-away device, the give-away device being adapted to move relatively to the feeler actuating means when the latter is arrested upon warp breakage. 90

4. A warp stop motion for looms having, in combination, warp detectors, a feeler, 100 feeler actuating means, a rotating cam for operating the feeler actuating means, and means mounted on the feeler actuating means and in engagement with the cam and having a motion relative to the feeler actuating means when the latter is arrested upon warp breakage. 105

5. A warp stop motion for looms having, in combination, warp detectors, a feeler, a rock shaft for the feeler, an arm rigidly 110 mounted on the rock shaft, a lever for actuating the rock shaft, connections between the lever and the arm, a rod for actuating the lever, a second lever for actuating the rod having a give-away device mounted 115 upon it, and a cam in engagement with the give-away device for operating the second lever.

6. A warp stop motion for looms having, in combination, warp detectors, a feeler, a lever for actuating the feeler and rotating means for operating the lever and a give-away device mounted slidably upon the lever and in engagement with the means for operating the lever, and adapted to be actuated relatively to the lever by the means for operating the lever when the latter is arrested upon warp breakage. 120

7. A warp stop motion for looms having, in combination, warp detectors, a feeler, 125

feeler actuating means including a rock shaft, an arm rigidly mounted on the rock shaft, a lever loosely pivoted on the rock shaft, connections between the lever and the arm, a feeler actuating lever, connections between the levers, a cam for operating the feeler actuating lever, and means mounted

upon and relatively movable to the feeler actuating lever adapted to move when said lever is stopped upon warp breakage.
